US00D958103S

(12) **United States Design Patent** (10) **Patent No.:** **US D958,103 S**
(45) **Date of Patent:** **** Jul. 19, 2022**

(54) **MOBILE PHONE**

(71) Applicant: **LG ELECTRONICS INC.**, Seoul

(KR)

(72) Inventors: **Seunghyun Ji**, Seoul (KR); **Hongkyu Park**, Seoul (KR); **Jonghak Lee**, Seoul (KR); **Jinki Min**, Seoul (KR); **Sojin Kim**, Seoul (KR)

(73) Assignee: **LG ELECTRONICS INC.**, Seoul (KR)

(**) Term: **15 Years**

(21) Appl. No.: **29/734,266**

(22) Filed: **May 11, 2020**

(30) **Foreign Application Priority Data**

Nov. 12, 2019 (JP) ..... 2019-025178 U

(51) **LOC (13) Cl.** **14-03**

(52) **U.S. Cl.**

USPC ..... **D14/138 AD**

(58) **Field of Classification Search**

USPC ..... D14/137, 496, 138 R, 138 AA, 138 AB,

(57) **CLAIM**

The ornamental design for a mobile phone, as shown and described.

DESCRIPTION

FIG. 1 is a front perspective view of the mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is an exploded view thereof, showing the mobile phone in an alternate configuration;

FIG. 9 is another front perspective view thereof, showing the mobile phone in an alternate configuration;

FIG. 10 is another front perspective view thereof, showing the mobile phone in an alternate configuration;

FIG. 11 is a front view of FIG. 10;

FIG. 12 is a rear view of FIG. 10;

FIG. 13 is a left side view FIG. 10;

FIG. 14 is a right side view FIG. 10;

FIG. 15 is a top plan view FIG. 10; and,

FIG. 16 is a bottom plan view FIG. 10.

The dash-dash broken lines depict portions of the mobile phone that form no part of the claimed design. The dash-dot-dash broken lines in FIG. 8 merely represent indicia that forms no part of the claimed design.

1 Claim, 16 Drawing Sheets
